UNITED STATES PATENT OFFICE.

JOHN F. O'CONNOR, OF CHICAGO, ILLINOIS, ASSIGNOR TO PRATT AND LETCHWORTH COMPANY, OF BUFFALO, NEW YORK, A CORPORATION OF NEW YORK.

CAST-STEEL BOLSTER FOR RAILWAY-CAR TRUCKS.

1,249,467.

Specification of Letters Patent. Patented Dec. 11, 1917.

Application filed February 26, 1914. Serial No. 821,299.

To all whom it may concern:

Be it known that I, JOHN F. O'CONNOR, a citizen of the United States, residing in Chicago, in the county of Cook and State of Illinois, have invented a new and useful Improvement in Cast-Steel Bolsters for Railway-Car Trucks, of which the following is a specification.

This invention relates to improvements in cast steel bolsters and more particularly to cast steel bolsters for railway car trucks.

Objects of the invention are to provide a bolster which comprises two members of like construction and each of which may be cast and molded from the same pattern; to provide a cast two-part bolster each of which is substantially channel-shaped in cross section from end to end; and to provide a two-part bolster having integral means thereon adapted to prevent sliding movement therebetween under bending strains.

The invention furthermore consists in the improvements in the parts and devices and in the novel combination of the parts and devices as herein shown, described or claimed.

In the drawing forming a part of this specification Figure 1 is a top plan view of a bolster embodying my improvements. Fig. 2 is a side elevation of the structure shown in Fig. 1, and Figs. 3 and 4 are enlarged, vertical sectional views taken on the lines 3-3 and 4-4, respectively, of Fig. 2.

In said drawing, the bolster is designated generally by the reference A and the same, as shown, comprises two members B B of like construction, each of which is a steel casting. Each member B is substantially channel-shaped in cross section from end to end, as shown most clearly in Figs. 3 and 4, and has a vertical web 10, upper flange 11 and lower flange 12, the upper flange 11 having a central horizontal portion 13, downwardly and outwardly inclined portions 14 and horizontal end portions 15. The lower flange 12 of each member B has a short horizontal central portion 16, upwardly and outwardly inclined portions 17 and horizontal end portions 18. Each member B is provided with a plurality of vertically extending strengthening ribs 19 on its inner side, guiding ribs 20 at its ends, and integral side bearing brackets 21. The upper and lower flanges 11 and 12 of each member of the bolster, at their end portions 15 and 18 are

provided with interengaging alternately arranged projections 22, 22, said projections being beveled in plan view as shown in Fig. 1 and also in vertical section as shown at 23 in Fig. 3 for a purpose hereinafter specified. The two members B are fitted together as shown in Fig. 1 and are securely held together by means of transversely extending headed rivets 24 at the ends thereof.

By providing the interengaging projections 22, 22 at the ends of the bolster members, the same are prevented from relative longitudinal movement or slippage when any bending forces are applied to the bolster at the center thereof.

The beveled ends of the projections 22 and the beveled faces between them interengage to draw the parts tightly together, tending to wedge the flanges of one part or member between the flanges of the other part or member, the parts being, however, sufficiently stiff to prevent the flanges of one side from entering actually between the flanges of the other.

The upper and lower flanges of the channel-shaped members are cut away at their center, as shown at 25, to receive the king pin as will be understood, the usual center bearing plate being indicated in dotted lines at 26 in Figs. 2 and 4.

From the preceding description it will be seen that the bolster which I have provided is of exceedingly strong, rigid construction and may be easily and cheaply cast.

Although I have herein shown and described what I now consider the preferred embodiment of my improvements, yet it will be understood that various changes and modifications may be made without departing from the spirit of the invention, and all such changes and modifications are contemplated as come within the scope of the claims appended hereto.

It will be noted that with the type of bolster which I have designed, the portions 14, 14 are placed under compression and the portions 17, 17 under tension when the bolster is in service and the members 19, 19 act as struts between said portions 14 and 17. With this construction a more rigid bolster is obtained than in those types of cast steel bolsters hitherto used wherein the upper and lower members of the bolsters are curved. With this latter construction, the curved portions under compression tend to buckle.

or bulge outwardly and the curved portions under tension tend to straighten out, thus decreasing the efficiency of the bolster.

I claim:

5 1. A bolster of the character described comprising two members of duplicated construction having interengaging vertically disposed integral means adapted to prevent relative sliding movement therebetween, 10 substantially as specified.

2. A bolster of the character described comprising two steel castings of duplicated construction rigidly secured together and each of which is provided with an integral member forming part of a side bearing bracket, substantially as specified.

15 3. A bolster of the character described comprising two steel members of like construction adapted to be molded and cast 20 from the same pattern, said members having flanges at their ends provided with vertically arranged, alternating, interengaging projections, substantially as specified.

4. A bolster for railway car trucks comprising 25 two steel castings of like construction each of which is substantially channel-shaped in cross section, said members being arranged with the flanges extending horizontally, the upper and lower flanges having at their ends, alternately arranged interengaging projections, substantially as specified.

30 5. A bolster of the character described comprising two steel castings of like construction riveted together, each of which is provided with flanges at its ends having integral, alternating, interengaging projections, each member being also provided with integral members forming half of a side bearing bracket, substantially as specified.

40 6. A bolster for railway car trucks comprising two steel channel shape castings ar-

ranged with the flanges thereof extending horizontally, interengaging projections on said castings, and means passing through 45 the webs of said castings for holding said projections in interengagement, substantially as specified.

7. A bolster for railway car trucks comprising two steel channel-shaped castings 50 arranged with the flanges thereof disposed horizontally and extending toward each other, said flanges having interengaging projections beveled in elevation and in plan, substantially as specified.

55 8. A bolster for railway car trucks comprising two channel-shaped members arranged with the flanges thereof extending toward each other and having interengaging projections tending to wedge the flanges 60 of one member between the flanges of the other.

9. A bolster for railway car trucks comprising two channel-shaped members arranged with the flanges thereof disposed 65 horizontally and extending toward each other, said flanges having interengaging surfaces tending to wedge the flanges of one member between the flanges of the other.

70 10. A bolster for railway car trucks comprising two steel channel shaped castings arranged with the flanges thereof disposed horizontally and extending toward each other, their adjacent edges being formed to interengage, and internal integral struts extending between the flanges of each member, substantially as specified.

75 Signed this 14th day of February, 1914,
in the presence of two witnesses.

JOHN F. O'CONNOR.
